UNITED STATES PATENT OFFICE.

GEORGE J. H. GOEHLER, OF RICHMOND, VIRGINIA.

SAFE.

No. 851,880.

Specification of Letters Patent.

Patented April 30, 1907.

Application filed January 10, 1907. Serial No. 351,615.

To all whom it may concern:

Be it known that I, GEORGE J. H. GOEHLER, a citizen of the United States of America, residing at Richmond, in the county of 5 Henrico and State of Virginia, have invented certain new and useful Improvements in Safes, of which the following is a specification, reference being had therein to the accompanying drawing.

10 This invention relates to certain new and useful improvements in safes, and relates specifically to an improvement in the construction of the interior box or casing of safes, sometimes known in the trade as the 15 safe "furniture."

The invention has for its object to provide an interior box or casing for safes constructed wholly of metal, and in which the sides, and the top and bottom of the box or casing 20 are made from one piece of material, and in which the back or rear wall of the box or casing is connected to the sides wholly without the use of rivets or like securing elements, and further, in which the dividing 25 partition of the interior box or casing is connected at its rear edge to the back of the rear wall of the box or casing, and at its forward edge, is connected to the top and to the bottom of said interior box or casing.

30 The invention resides in the novel construction and arrangement of parts to be hereinafter more fully described, and then particularly claimed.

In describing the invention in detail, reference will be had to the accompanying drawings, forming a part of this application, and wherein like numerals of reference will be employed to designate like parts throughout the several views of the drawings, in which:

35 Figure 1 is a horizontal sectional view of a safe embodying my improvement; Fig. 2 is a detached detail perspective view of the interior box or casing, this view showing the dividing partition removed, and also illustrating the manner in which the ends of the 40 one-piece blank are joined together, and the manner in which the back or rear wall is joined to the sides; Fig. 3 is a detached detail perspective view partly broken away, of 45 the dividing partition of the box or casing; Fig. 4 is a detail sectional view of a part of the back or rear wall and a part of the top of the interior box or casing, said view being taken on line 4—4 of Fig. 2; Fig. 5 is a detail sectional view of a part of one side wall, and of the back or rear wall, said view being

taken on line 5—5 of Fig. 2; Fig. 6 is a detail sectional view of a part of one side wall and a part of the bottom of the interior box or casing, said view being taken on line 6—6 of 60 Fig. 2; Fig. 7 is a detail sectional view of a part of the dividing partition of the interior box or casing, said view being taken on the line 7—7 of Fig. 3; Fig. 8 is a detail sectional view of a part of the bottom of the interior box or casing, showing in side elevation a part of the dividing partition of said box or casing and the rod by means of which the front or forward edge of said partition is fastened to the top and bottom of the box or casing. Fig. 9 is a detail perspective view 70 partly broken away of a modified construction of the dividing partition for the box or casing; Fig. 10, is a detail sectional view thereof taken on the line 10—10 of Fig. 9.

In the accompanying illustration of my invention, I have selected for illustrative purposes, a safe of small size in which there is employed merely the box or casing *per se*, and a single dividing partition to separate 80 the interior of the box or casing into two compartments. The invention is confined to the construction of the box or casing, and it will consequently be understood that while I have shown and will describe herein the 85 box or casing having a single interior partition, that I do not confine or limit myself to this particular interior construction of the box or casing, as it will be readily understood that where additional partitions, whether 90 they be vertical or horizontal, and also where drawers are desired, they may readily be provided.

The box or casing forming the subject-matter of this application, is constructed of 95 a sheet of material, preferably sheet iron, which is bent or shaped to form the top 1, sides 2, 2, and bottom 3, the ends of said blank being brought together, and interlocked as shown at 4 in Fig. 2. The interlocked seam 4 is usually formed along the base of the box on the outside, the free edge or end of the blank at the termination of the one side wall being bent outwardly and upwardly to form a groove, the opposite edge of the blank, which is the termination of the bottom, being bent upwardly and downwardly to interlock in said groove. After the ends of the said sheet metal blank have been thus interlocked, the seam may be compressed to flatten the same and bind the interlocking ends of the blank together. The 105 110

back or rear wall 5, is formed from a sheet of material of similar nature, but separate from the blank from which are formed the sides, top and bottom of said box or casing. This 5 back or rear wall 5 is made of a size slightly larger than the dimensions of the completed box or casing, so as to provide at the edges of the blank from which said back or rear wall 5 is formed, sufficient surplus material 6, to 10 provide for the crimping or turning in such surplus material to form an interlocking seam with the top 1 and with the sides 2, as shown at 7 in detail Figs. 4 and 5 respectively. This interlocked seam is of the same nature 15 as the interlocked seam 4 previously described. In some instances, where an interlocked seam is provided between the back or rear wall 5 and the top 1, a similar interlocked seam may not be necessary with the 20 bottom 3, though generally it is the practice to interlock the lower edge of the back or rear wall 5 with the rear edge of the bottom 3 in the same manner as is shown for the interlock between the back or rear wall and the 25 top, and between the back or rear wall and the sides.

The front edges of the blank from which the top, the side walls and the bottom are formed are flanged along the respective front 30 edges of said parts as shown at 8, so as to fit with the door frame 9 of the safe body, as clearly shown in Fig. 1 of the drawings.

In the present illustration of the invention I have shown the box or casing provided 35 with a vertical partition 10, for separating the interior of the box or casing into two compartments. This partition 10, is formed of sheet metal similar to the remainder of the box or casing, and has its rear edge turned at 40 right angles to the body of the partition to form a flange 11, which fits against the rear wall, and is secured thereto in any desired manner as by rivets 12. The front edge of this partition may be firmly secured to the 45 top and bottom of the box or casing by a post 14, having its ends projecting respectively into the top and bottom of the box or casing, and riveted therein; with the front edge of the said partition wrapped around 50 the post as plainly shown in Figs. 1, 3 and 7. In Figs. 9 and 10, I show another method of securing said partition to the top and bottom of the box or casing, which consists in wrapping or folding the front edge of said partition upon itself a number of times, so as to form a vertical post 15, of sufficient rigidity to take the place of the post 14, the ends 16 of the post 15 being extended beyond the upper and lower edges of the partition, and extended through the top and bottom of the box or casing, and then bent outwardly at right angles as shown in Fig. 9, so as to be clenched with the said top and bottom of the casing.

65 The construction of my improvement in

the interior box or casing of safes will, it is believed, be clearly apparent from the foregoing description taken in connection with the accompanying drawing. I desire however to call particular attention to certain 70 advantages resulting from the use of an all metal interior box or casing, first that such construction makes the safe mold and damp proof, as all joints along the edges are perfectly close, and the front end of the box fits 75 neatly with the door frame, the step like flanges 8 being constructed to match neatly with said door frame, and matching neatly therewith, requires no fastening to said frame, as the filling in the safe (which usually 80 consist of Portland cement poured into the safe in a semi-liquid state) will compress the flanges 8, firmly into seating engagement with the door frame 9. Further, the dangers incident to a wood-lined safe are entirely 85 obviated, all parts in the box or casing and the latter *per se* being constructed of sheet iron. Dispensing with wood-work in the interior of the box or casing also enables me to provide more space for the cement filling which is very desirable, especially in 90 small sized safes.

Having fully described my invention, what I claim as new, and desire to secure by Letters Patent is:

1. A sheet metal interior box or casing for safes, comprising a body formed of one sheet of metal and comprising the top wall, the side walls and the bottom wall, a back or rear wall having an interlocking seam-engagement with the rear edges of said body, and an interior partition flanged at its rear edge and secured to the rear wall, and means for securing the front edge of said partition to the top and bottom walls of the 100 105 body.

2. A sheet metal interior box or casing for safes, comprising a body formed of a single sheet of metal and comprising the top wall, the side walls, and the bottom wall of the 110 box, a back or rear wall secured to the rear edge or end of said body, and an interior partition secured at its rear edge to the said back and at its forward edge to the top and bottom wall.

3. A sheet metal interior box or casing for safes, comprising a body formed of a single sheet of metal comprising the top wall, the side walls and the bottom wall, a back or rear wall secured to said body, an interior partition within the body, a post carried by the forward edge of said partition having its ends secured in the top wall and bottom wall of the body, and stepped-flanges carried by the front end of said body.

4. In safe construction, a sheet metal interior box or casing comprising a body formed from a blank of sheet metal having its ends secured together by an interlocking seam, stepped-flanges carried by the front 115 120 125 130

end of said body, a rear or back wall having its edges secured by interlocking seams with the rear end of the body, and an interior partition secured along its rear edge to the rear wall and at its front edge by a post secured in the top wall and bottom wall.

5. In safe construction, a sheet metal interior box or casing comprising a top wall, side walls, a bottom wall, and a rear or back wall, and an interior partition having a

flanged rear edge secured to the rear wall and its forward edge fastened to a post secured in the top wall and bottom wall of the box or casing.

In testimony whereof I affix my signature 15
in the presence of two witnesses.

GEORGE J. H. GOEHLER.
